LOADING MACHINE

Frank Cartlidge, Chicago, Ill., assignor to Goodman Manufacturing Company, Chicago, Ill., a corporation of Illinois

Application April 21, 1932, Serial No. 606,619
Renewed October 11, 1934

25 Claims. (Cl. 262—9)

This invention relates to loading machines of the type adapted to load coal in mines at the working face, and has among other objects to provide a new and improved gathering and loading element for picking up and loading coal or like material.

One of the problems encountered in loading coal is that under certain conditions and in certain kinds of coal seams, the coal when shot down, does not readily break up into small pieces but frequently comes down as one mass of material. Another condition encountered is that the force of the explosive charge at the rearward end of the drill hole, which is usually positioned adjacent the inner end of the kerf cut by the mining machine, may wedge the coal between the mine roof and the mine bottom. This wedged coal or these large lumps of coal continually impede the progress of the loading operation and necessitate the employment of man power to break up the coal so it may readily be gathered by the gathering and loading mechanism. One of the objects of my invention is to provide a means associated with the gathering and loading mechanism which will break up these large lumps of material and break down coal which has been wedged between the mine roof and mine bottom or which is hanging from the mine roof and coal face.

My invention may be more clearly understood with reference to the accompanying drawings wherein:

Figure 1 is a side elevation of a device embodying my invention;

Figure 2 is a top plan view of the device shown in Figure 1;

Figure 3 is an enlarged top plan view of the forward portion of the device shown in Figure 1 with parts broken away and in section to more clearly show the details thereof;

Figure 4 is an enlarged side elevation of the forward portion of the device shown in Figure 1 with parts broken away and in section to more clearly show the details thereof;

Figure 5 is an enlarged plan view of the device shown in Figure 1 showing certain other parts broken away and in section than are shown in Figure 3;

Figure 6 is an enlarged sectional view taken substantially on line 6—6 of Figure 3; and

Figure 7 is an enlarged sectional view taken substantially on line 7—7 of Figure 3.

Referring now in particular to the drawings, the main elements of the embodiment of my invention illustrated are similar to those disclosed

in a prior application bearing Serial No. 472,701, filed by me August 2, 1930, and entitled Improvements in loading machines, and consist of a wheeled truck or main frame 10 having an inclined gathering and loading element 11 in front of the main frame, and a discharge conveyor 12 extending from beneath the rear end of said gathering and loading element and upwardly and rearwardly therefrom overhanging the rear end of the main frame 10 for discharging material 10 into suitable receptacles such as mine cars.

A suitable means is provided for driving the main operating parts, which means herein comprises an electric motor 13. The electric motor 13 has driving connection with the truck wheels 15 for driving the loading machine about the mine and for feeding the loading element into the material to be loaded. The electric motor 13 also serves as a driving means for the operating parts of the gathering and loading element 11, for raising or lowering said gathering and loading element, and for swinging said gathering and loading element about a vertical axis. The details of the drive to the main operating parts are similar to those disclosed in my aforementioned prior application so will not herein be shown or described in detail.

The gathering and loading element 11 comprises an inclined conveyor frame 14 supported between a pair of upright side plates 15 for pivotal movement with respect thereto about a horizontal axis disposed adjacent the rearward end thereof.

The upright side plates 15 are in turn supported on the main frame 10 for swinging the inclined conveyor frame 14 about a vertical axis and positioning the gathering and loading element 11 for gathering from various sections in the working place. The means for swinging the upright side plates 15 about a vertical axis, and the inclined conveyor frame 14 about a horizontal axis, are not herein shown or described since they are no portion of my present invention and are fully disclosed in my aforementioned prior application.

The inclined conveyor frame 14 is provided with a central portion or pan 16 forming a surface for moving material therealong and sides 17 extending upwardly and downwardly therefrom, the upper portion of which sides are flared outwardly to form in effect a hopper for retaining and deflecting material on the pan 16. Suitable means are provided for moving loose material along the central portion or pan 16 of the inclined conveyor frame 14 which may be of any construction, but which is herein preferably shown as

being a flight conveyor indicated by reference character 19.

The flight conveyor 19 may be of any suitable construction, but is herein preferably shown as comprising a pair of parallel spaced chains 20 having flights 21 carried therebetween in a suitable manner. The chains 20 are trained around suitable sprockets (not shown in detail) adjacent the rearward end of the conveyor frame 14 10 keyed on a transversely extending drive shaft 23 coaxial with the axis of pivotal connection of the conveyor frame 14 with the upright side plates 15. The transversely extending drive shaft 23 is driven from the motor 13 by means of a suitable geared reduction drive, and chain and sprocket drives generally indicated by reference character 24 in a manner similar to that disclosed in my hereinbefore mentioned prior application.

20 The conveyor chains 23 extend forwardly from the sprockets on the shaft 23 along the underside of the pan 16 of the conveyor frame 14 over adjustable idler rollers 25 under drive sprockets 26 keyed on a transversely extending drive shaft 27 25 and forwardly from said drive sprockets and around drive sprockets 29 keyed on a transversely extending shaft 30 disposed adjacent the forward end of the flight conveyor 19. From thence the conveyor chains 28 extend rearwardly along the top surface of the central portion or pan 16 of the conveyor frame 14 to the sprockets on the shaft 23.

30 The idler rollers 25 may be adjusted for adjusting the tension of the conveyor drive chains 20 in a usual manner, which is illustrated in Figure 4 but is not herein described in detail since it is no portion of my invention.

Referring now in particular to the gathering and loading element and several of the novel features of my invention, inclined aprons 31 are 40 provided on a forward portion of the inclined conveyor frame 14 adjacent each side of the flight conveyor 19. The inclined aprons 31 are inclined at a greater angle of incidence with respect 45 to the ground, upon which the machine rests, than the flight conveyor 19 and are spaced closer together adjacent their forward ends than at their rearward ends. A shoe indicated at 32 is disposed adjacent the forward underportion of each inclined apron 31 and abuts the forward end thereof so the entire inclined conveyor frame 14 may rest on said shoe on the mine bottom, and so the inclined aprons 31 with the shoes 32 will form in effect a wedge which may be wedged 50 under the broken down material which it is desired to load. The rearward portions of the inclined aprons 31 merge into and are connected to the outwardly flared sides 17 of the conveyor frame 14. With reference to Figure 3, it may be seen that the angle of the inner sides of the inclined aprons 31 and the outwardly flared sides 17 of the inclined conveyor frame 14 is such as to 55 deflect material onto said conveyor and to prevent the gathering mechanism from carrying the material around past the conveyor to the opposite side of said apron.

60 The aprons 31 serve to support a portion of the gathering and loading mechanism which herein comprise endless chains 33 movable in fixed orbital paths in guides 34 fixed to the top portion of each apron 31. The endless chains 70 75 have gathering arms 35 connected thereto and spaced therealong at definite intervals determined by the size of material which is being loaded and the speed of said endless chains.

The gathering arms 35 are provided with a plurality of bits 36 on their outer ends to aid in breaking up large or tight pieces of material so it may readily be moved onto the flight conveyor 19. The endless chains 33 are driven from the flight conveyor 19 by means of bevel gear drives indicated at 37 driven from opposite ends of the transversely extending drive shaft 27, which bevel gear drives are connectible with shafts 38 extending perpendicularly to the aprons 10 31 for driving said shafts. The shafts 38 are journaled in suitable bearing means secured to the underportion of the aprons 31 and have sprockets 49 keyed thereto adjacent the upper side of the aprons 31, which sprockets mesh with 15 and drive the endless chains 33.

With reference to Figures 2 and 3, it may be seen that the paths of the gathering arms 35 are such that a dead space is left between said gathering arms. Where the material is tightly wedged between the mine roof and bottom, or where the lumps are large, it is impossible to feed the gathering element into the loose material due to the material which collects in this dead space. Various means have been provided for eliminating this dead space which include the cutting back of the forward end of the apron and spacing the gathering arms closer together towards the center line of the conveyor so said gathering arms may gather the material which is forced into this cut-away portion of the apron. I herein provide a new and improved means of a novel construction for gathering and breaking up material in the dead space left by the gathering arms which comprises a rotatable bar 41 35 having bits 43 therein.

The rotatable bar 41 has a plurality of sprockets 44 keyed at opposite ends thereof and is journaled in a suitable bearing support extending forwardly from the flight conveyor 19. Drive 40 sprockets 45 are provided on opposite ends of the transversely extending drive shaft 39. The drive sprockets 45 are connected with the sprockets 44 for driving said sprockets by means of suitable drive chains indicated at 46. A plate 47 extends 45 forwardly from the underportion of the inclined conveyor frame 14 adjacent the lower side of the parallel spaced chains 29 and drive sprockets 28 to a point adjacent the mine bottom rearwardly of the rotatable bar 41. An arcuate shaped 50 guide plate 48 extends upwardly and inwardly from the forward end of the plate 47 and conforms substantially to the path of the bits 43 on the rotatable bar 41 and is tied to an arcuate shaped guide plate 49 conforming to the path 55 of the parallel spaced chains 29 by means of a plate 50. A baffle plate 51 is secured to the upper side of the plate 50 and extends forwardly and downwardly therefrom to a point adjacent the rotatable bar 41. The baffle plate 51 is provided with a series of slots 52 therein which are adapted to receive the bits 43 in the rotatable bar 41.

It should be noted that the bits 43 extend outwardly from the rotatable bar 41, that their forward surface forms a straight line perpendicular to a plane which intersects the axis of said rotatable bar, and that the angle between said bits and the baffle plate 51 is such that when said bits approach the slots 52 and are moving material upwardly onto the baffle plate 51 and plate 50, that said bits will deflect the material onto the plate 50 where it may be engaged by the gathering arms 35 instead of crushing said material between the baffle plate 51 and slots 52. 70 75

It may thus be seen that as the entire gathering and loading element 11 is advanced into the material which is being loaded the bits 43 in the rotatable bar 41 will engage the material left 5 in the dead space between the gathering arms 35 and move said material onto the plate 50 where it may be deposited onto the flight conveyor 19 by means of the gathering arms 35. Furthermore, it should be noted that the bits 43 are so arranged 10 that they may cut into large lumps of material and break said material up so it may readily be gathered onto the flight conveyor 19 by the gathering arms 35 and permit the entire gathering and loading element 11 to be advanced 15 into the material which is being loaded.

Referring now in particular to the means for breaking down the coal or material wedged between the mine roof or mine bottom, a plurality of reciprocably movable picks 55 operable upon 20 operation of the gathering arms 35 and driven thereby are provided. The picks 55 are carried on the top surface of the guides 34 for the endless chains 33 and extend longitudinally thereof. Inasmuch as the picks 55 on each guide 34 and 25 means for operating said picks are of a similar construction, one only will herein be shown and described in detail.

Referring now in particular to Figures 3, 4, and 30 6 showing the details of the mechanism for reciprocating each pick 55, a cam member 56 is keyed on the upper end of the shaft 39 and is journaled in suitable bearing supports secured to the guides 34. The cam member 56 is adapted to engage a rider 57 secured to the lower end of a 35 connecting arm 58. The cam member 56 has an engaging surface of substantially a crescent shape so as to move the connecting arm 58 rearwardly with respect to the guide 34 against a suitable compression spring 59 and release said connecting 40 arm at a certain predetermined point to permit forward movement of the pick 55 actuated by said compression spring.

The connecting arm 58 extends forwardly from the rider 57 and is formed integral with a pick 45 supporting member 60 having the pick 55 attached to its forward end in a suitable manner; as, for instance, a pin indicated at 61. The portion of the pick supporting member 60 rearwardly of the pick 55 and forwardly of the cam 56 is of a box 50 like construction and encloses the compression spring 59 and is itself enclosed in a guide member 62 extending longitudinally of the guide 34. Suitable longitudinally extending guides 63 are formed in the lower rearward end of the pick supporting member 60 which are engageable with a 55 guide 64 formed by the lower leg of an angle 65 by reducing the width of said leg. The other leg of the angle 65 extends perpendicularly to the guide 34. The compression spring 59 is interposed between the forward end of the leg of the angle 65 perpendicular to the guide 34 and an inner end 66 of the supporting member 60. Thus rotation of the cam member 56 moves the connecting arm 58 of the supporting member 60 60 rearwardly with respect to the guide member 62 which causes compression of the compression spring 59, and as the cam member 56 is released from the rider 57, the pick 55 is impelled forwardly by means of the compression spring 59 to a 65 position adjacent the forward end of the gathering arms 35 as may be clearly seen with reference to Figure 4.

Suitable means are provided to lock the pick 55 in an inoperative position, which means herein 70 comprises a latch member 67 which is adapted to

move through suitable apertures in the guides 34 to engage the forward side of the inner end 66 of the supporting member 60 and hold the spring 59 in a compressed position and prevent release thereof. A slight amount of clearance is provided between the forward side of the inner end 66 of the supporting member 60 and the latch member 67 when the cam 56 has moved the pick supporting member 60 in an extreme rearward position with respect to the guide member 62 to 10 permit said latch member to be disengaged from said pick supporting member.

The latch member 67 is formed integral with and extends upwardly from the forward end of one arm of a bell crank lever 68 pivotally supported on a horizontally extending pin 69. The opposite arm of the bell crank lever 68 extends downwardly from the pin 69 and has a connecting rod 70 pivotally connected thereto, which connecting rod extends rearwardly from said bell crank 20 lever and has its rearward end connected to a coupling member 71.

The coupling member 71 is pivotally connected adjacent its central portion to the upper end of a lever 72 pivotally supported on the vertical portion of the sides 17 of the inclined conveyor frame 14 intermediate its ends. The lower end of lever 72 has the end of a transversely extending shaft 73 secured thereto in a usual manner. The opposite end of the transversely extending shaft 73 30 is secured to the lower end of the lever 72 on the opposite side of the conveyor frame 14, which lever is connected with the bell crank lever 68 for the opposite latch member 67. The picks 55 may therefore be locked in an inoperative position or rendered operative from one side of the machine. An operating rod 75 is connected to the opposite end of the coupling member 71 on the right hand side of the machine and has a suitable gripping means formed on its rearward end 40 (not shown) which is adapted to be engaged by suitable locking means in a usual manner for holding the latch member 67 in a locked or unlocked position. The rearward end of the operating rod 75 and gripping means thereon is so 45 located as to be remote from the forward portion of the inclined gathering and loading element to prevent injury to the operator of the machine in cases where the picks 55 break down the entire coal face causing it to fall on the forward portion of the machine, which condition is very desirable 50 inasmuch as it eliminates a portion of the gathering operation.

It may now be seen that a new and improved gathering and loading element has been provided 55 for a loading machine which is of such a construction that it may operate equally as well in places where the lumps of coal are large, or where the coal is tightly wedged between the roof and bottom as in places where the coal is loose. It may also be 60 seen that the gathering and loading element of the device of my invention is so constructed that a maximum amount of material may be gathered with a minimum amount of physical labor, and that the machine has been constructed with a 65 view toward uniform feeding into the material to be loaded for loading said material at a maximum uniform rate.

While I have herein shown and described one embodiment of my invention, it will be understood that the construction and arrangement of the various parts may be altered or changed without departing from the spirit or scope thereof. Furthermore, I do not wish to be construed as 70 limiting myself to the specific form illustrated, 75

excepting as it may be limited in the appended claims.

I claim as my invention:

1. In a loading machine, gathering and loading mechanism therefor comprising an inclined conveyor, a plurality of endless chains having gathering arms thereon spaced on each side of said conveyor, said chains extending forwardly of said conveyor and being movable in orbital paths in a plane inclined with respect to the horizontal, and a rotatable bar having gathering means thereon disposed forwardly of said conveyor between said endless chains.

10 2. A loading machine as set forth in claim 1 wherein the rotatable bar is disposed transversely of the conveyor and is provided with a plurality of bits.

15 3. In a loading machine of the class described, gathering and loading mechanism therefor comprising an inclined conveyor, an inclined apron disposed on each side of said inclined conveyor, an endless chain having gathering arms thereon guided on each apron for movement in orbital paths in planes parallel to the planes of said aprons, breaking mechanism extending forwardly of said conveyor and operable simultaneously with said endless chains, and a transversely extending rotatable bar having gathering means thereon supported between said aprons forwardly of said inclined conveyor.

20 4. A loading machine as set forth in claim 3 wherein the rotatable bar is driven by the inclined conveyor.

25 5. A loading machine as set forth in claim 3 wherein the gathering means on the rotatable bar comprise bits.

30 6. A loading machine as set forth in claim 3 wherein the rotatable bar is driven by the inclined conveyor, wherein the gathering means on said rotatable bar comprises bits and wherein a baffle plate having slots adapted to register with the bits on said rotatable bar extends forwardly of the conveyor towards said rotatable bar.

35 7. A loading machine as set forth in claim 3 wherein the rotatable bar is driven by the inclined conveyor, wherein the gathering means on said rotatable bar comprises bits, wherein a baffle plate having slots adapted to register with the bits on said rotatable bar extends forwardly of the conveyor towards said rotatable bar and wherein the angle of the bits with respect to the baffle plate as said bits approach the baffle plate is such as to deflect material along said baffle plate onto said inclined conveyor.

40 8. A loading machine as set forth in claim 3 wherein the breaking mechanism comprises a reciprocably movable forwardly extending pick supported on each apron.

45 9. A loading machine as set forth in claim 3 wherein the picks are reciprocably moved by the mechanism for driving the endless chains.

50 10. A loading machine as set forth in claim 3 wherein the breaking mechanism comprises a reciprocably movable forwardly extending pick supported on each apron and wherein the picks are reciprocably moved by cam and spring mechanism driven by the mechanism for driving the endless chains.

55 11. In a loading machine, gathering and loading mechanism therefor comprising an inclined conveyor, a plurality of endless chains having gathering arms thereon spaced on each side of said conveyor, said chains extending forwardly of said conveyor and being movable in orbital

paths in a plane inclined with respect to the horizontal, a rotatable bar disposed transversely and forwardly of said conveyor having a plurality of bits extending outwardly therefrom and a baffle plate extending forwardly of said conveyor towards said rotatable bar and having a plurality of slots therein adapted to register with the bits on said rotatable bar.

60 12. A loading machine as set forth in claim 11 wherein the angle of the bits with respect to the baffle plate as said bits approach said baffle plate is such as to deflect material along said baffle plate onto said inclined conveyor.

65 13. In a loading machine, gathering and loading mechanism therefor comprising an inclined conveyor, a plurality of endless chains having gathering arms thereon spaced on each side of said conveyor, said chains extending forwardly of said conveyor and being movable in orbital paths in a plane inclined with respect to the horizontal, breaking mechanism extending forwardly of the conveyor operable simultaneously with the endless chains, and a rotatable bar having gathering means thereon disposed forwardly of said conveyor and extending transversely with respect thereto between said endless chains.

70 14. In a loading machine, gathering and loading mechanism therefor comprising an inclined conveyor, a plurality of endless chains having gathering arms thereon spaced on each side of said conveyor, said chains extending forwardly of said conveyor and being movable in orbital paths in a plane inclined with respect to the horizontal, breaking mechanism comprising a plurality of reciprocably movable forwardly extending picks and a rotatable bar having gathering means thereon disposed forwardly of said conveyor between said endless chains.

75 15. In a loading machine, gathering and loading mechanism therefor comprising an inclined conveyor, a plurality of endless chains having gathering arms thereon spaced on each side of said conveyor, said chains extending forwardly of said conveyor and being movable in orbital paths in a plane inclined with respect to the horizontal, breaking mechanism comprising a plurality of reciprocably movable forwardly extending picks reciprocably driven by the mechanism for driving the endless chains and a rotatable bar having gathering means thereon disposed forwardly of said conveyor between said endless chains.

80 16. In a loading machine, gathering and loading mechanism therefor comprising an inclined conveyor, a plurality of endless chains having gathering arms thereon spaced on each side of said conveyor, said chains extending forwardly of said conveyor and being movable in orbital paths in a plane inclined with respect to the horizontal, a rotatable bar having gathering means thereon disposed forwardly of said conveyor between said endless chains, and breaking mechanism extending forwardly of the conveyor comprising a plurality of reciprocably movable forwardly extending picks operable simultaneously with and reciprocated by the mechanism for driving the endless chains.

85 17. A loading machine as set forth in claim 16 wherein the picks are reciprocably moved by cam and spring mechanism.

90 18. A loading machine as set forth in claim 16 wherein the picks are reciprocably moved by cams driven from the mechanism for driving the endless chains and resilient members having connection with said picks.

19. In combination in a loading machine, gathering and loading mechanism therefor comprising a conveyer, gathering means on each side of said conveyer extending from a point disposed forwardly of the forward end thereof for moving material therebetween onto said conveyer, and a transversely disposed rotatable bar having gathering means thereon disposed forwardly of said conveyer between said gathering means.
- 5 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450
19. In combination in a loading machine, gathering and loading mechanism therefor comprising a conveyer, gathering means on each side of said conveyer extending from a point disposed forwardly of the forward end thereof for moving material therebetween onto said conveyer, extending along and driven by each of said gathering means.
23. In combination in a loading machine, gathering and loading mechanism therefor comprising a conveyer, gathering means on each side of said conveyer extending from a point disposed forwardly of the forward end thereof for moving material therebetween onto said conveyer, breaking mechanism extending forwardly of said conveyer and disposed above and operated by said gathering means, and a transversely disposed rotatable bar having gathering means thereon disposed forwardly of said conveyer between said gathering means.
24. A loading machine as set forth in claim 23, wherein the rotatable bar is provided with a plurality of bits, and wherein a baffle plate having slots adapted to register with the bits on said rotatable bar extends forwardly of the conveyer towards said rotatable bar.
25. A loading machine as set forth in claim 23, wherein the rotatable bar is disposed transversely of the conveyer and is provided with a plurality of bits, wherein a baffle plate having slots adapted to register with the bits on said rotatable bar extends forwardly of the conveyer towards said rotatable bar, and wherein the angle of the bits with respect to the baffle plate as said bits approach said baffle plate is such as to deflect material along said baffle plate onto said conveyer.
